UNITED STATES PATENT OFFICE

1,940,908

GUARD FINGER AND LEDGER PLATE FOR
MOWING MACHINES

John R. Farris, Salt Lake City, Utah

Application July 24, 1931. Serial No. 552,924

4 Claims. (Cl. 56—311)

This invention comprises novel improvements in guard finger and a ledger plate means adapted to be used as parts of the cutting apparatus of a mowing-machine.

5 The mowing-machine comprises, as usual, the necessary instrumentalities to operate the cutting knife or sickle bar with its customary means for lifting and shifting the cutting apparatus. These details of the mowing-machine are omitted from 10 the drawing, as they form no part of this invention other than they are used in combination with the guard finger and the ledger plate.

For the guard fingers such as now used, the ledger plate is either riveted to or fastened with 15 screws to the guard finger. The known object of the ledger plate is to provide a cutting edge to meet the cutting edge of the knife or sickle bar mounted on the cutting apparatus, and reciprocating in the guard fingers through the instrumentalities for the actuating means.

20 It is well known that the ledger plates become dull and incapacitated through use, and also broken or nicked by coming into contact with gravel and rocks encountered in the movement 25 of the mowing-machine over the surface being mowed. The ledger plates under the above conditions must be removed and replaced by new ones, if the mowing-machine is to perform its functions effectually.

30 To replace the ledger plates now commonly used is an irksome task, due to the rivets or screws, because rivets must be chopped off and driven out, and screws become rusted in the structure, and sometime the heads are broken off in 35 endeavoring to remove them.

The object of this invention is to overcome this difficulty, and to improve the mounting and removal of the ledger plates. In the practice of my 40 invention, the ledger plates may be removed or mounted in a very short interval of time, and with very ordinary and simple tools, such as a punch, chisel or flat elongated piece of metal, or other suitable tool.

This invention is fully disclosed in the following specification, of which the accompanying drawing forms a part, in which the separate parts of my improvements are designated by suitable reference characters in each of the views.

45 Figure 1 is a top view of a guard finger with the ledger plate mounted therein.

50 Figure 2 is a longitudinal sectional view taken about line 2—2 in Figure 1, showing the means for connecting the ledger plate to the guard finger.

55 Figure 3 is a sectional fragmentary view of a

guard finger and the ledger plate, showing the interposition of a tool therein and thereunder, with a hammer adjacent one of the tools, to illustrate the simple method of mounting or removing the ledger plate.

Figure 4 is a cross sectional view of the guard finger and ledger plate taken on line 4—4 in Figure 1 showing the relation of the ledger plate to the guard finger.

In the drawing forming a part of this specification I have shown the guard finger A in which the ledger plate B is removably mounted therein. The guard finger is provided with an aperture 1, adapted to receive a rivet or other suitable member for the purpose of securing the guard finger in fixed relation to its associate part or parts of the mowing-machine. Adjacent the pointed end of the guard finger there is provided a pocket or receiving socket 2, the lower wall or floor 3 of which is provided with a curvature or contour 4 leading upwardly in the guard finger A. The upper integral wall 5 of the socket extends from before backward, and is so positioned that it forms a transverse slot 6 with the ledger plate B when mounted in the guard finger.

This transverse slot is provided to receive the sickle or knife that may be reciprocated therein. Adjacent the entrance of the pocket or receiving socket there is placed a downwardly extending and transverse rib 7, this rib is adapted to form 85 a fulcrum or support against which the ledger plate rests when mounted in the guard finger and tending to force the rear end of the plate downwardly.

The upper wall 5 has also a semi-circular or other suitable shape notch 8, adapted to permit the mounting of a tool used in mounting or removing the ledger plate. The guard finger is provided with laterally extending arms 9 and 9', these arms provide a bearing surface for the 95 sickle or knife. A notch or depression 10 is provided intermediate the arms, and of a depth equal substantially to the thickness of the ledger plate. A recess or depression 11 of a suitable configuration is provided in the guard finger for the reception on the rear extremity of the ledger plate. The wall 11' of the recess 11 is provided with an inclined face adapted to receive the complementary bevelled face formed on the rear end of the ledger plate. The guard finger is also provided with a 100 series of depressions 12, 13 and 14 to reduce the weight of the guard finger.

The ledger plate B is provided at one end with a reduced integrally formed portion 15, forming 105 with the ledger plate shoulders 16 and 16'. The 110

reduced portion is mounted in the socket 2, and the socket is provided to prevent lateral displacement of the ledger plate at this extremity. The other extremity or end 17 is suitably formed, and 5 is mounted in the recess of depression formed in the guard finger provided for its reception. Lateral displacement is prohibited at this end by the squared shoulders, flanges, or ribs, 24 and 24' that form a part of the perimeter that bounds the 10 socket or depression 11 formed for the ledger plate reception. An aperture 18 is provided in the ledger plate for the reception of a suitable tool 19, to be mounted therein, for the removing or mounting 15 of the ledger plate B. 20 indicates a hammer in proximity to the tool 19, depicting its use in conjunction with the removing or mounting tool. 21 indicates a tool and represents vividly its position in removing the ledger plate, it being used as a lever to break the interlocking connection 20 between the ledger plate and the guard finger. The ledger plate is slightly tapered as at 23, so that it will conform to the contour of the socket wall or floor.

In practice of my invention, if it is desired to 25 remove a ledger plate, a tool is inserted in the depression 10 and pushed under the plate B, and forced downward in the direction of the arrow shown in Figure 3, this movement forces the plate up and over the angled or bevelled end of the 30 socket 11. The tool is next placed in the aperture in the ledger plate, and the tool is struck, thus releasing the plate from the socket 2 in the guard finger.

To mount the ledger plate, which is of spring 35 metal, the plate is driven into the socket 2, and because of the special construction of the socket, and the end portion of the ledger plate, the end is caused to follow the curvature or contour of the bottom wall of the socket 2. This causes the 40 other extremity to be sprung downwardly or take a downward position, when the plate has reached the limit of its movement in the socket 2, the other end or extremity is then lifted up and then forced down and into place in the socket prepared 45 therefor, the bevelled or angled edge of the ledger plate engages or springs against the complementary face formed on the socket wall, adapted to interlock the ledger plate in the socket.

It will be apparent from the structure shown 50 that the ledger plate is securely held in place by the resiliency inherently within itself, it being made of a spring steel plate.

It will be further noted that the top of the ledger plate is flush with the top of the arms 9 55 and 9'.

In accordance with the patent statutes I have set forth in a specific manner required thereby one complete embodiment of my invention, but it is to be understood that this is only for illustrative purposes and that the invention is capable of assuming other forms than that illustrated, and that the claims hereto annexed are not to be limited to the specific devices illustrated, except as is specifically recited therein.

Having thus described my invention what I 85 claim as new and desire to secure by Letters Patent of the United States, is—

1. In combination, a guard finger, a ledger plate therefor, a socket having an upwardly contoured lower floor, the ledger plate mounted in the socket and having an end cooperating with contoured lower floor, and means for interlocking the ledger plate in the guard finger. 90

2. In combination, a guard finger, a ledger plate therefor, a socket having contoured lower floor, a transverse rib thereabove and positioned adjacent the socket entrance, a second socket remote therefrom, the ledger plate having a reduced and tapered end, said end mounted in the socket having the contoured floor, and cooperating with 100 the transverse rib, the other end of the ledger plate mounted in the remote socket, and means for interlocking the ledger plate in the remote socket. 95

3. In combination, a guard finger, a ledger plate therefor, a socket having a contoured floor, a rib thereabove and adjacent the entrance thereof, a ledger plate having a reduced and tapered end mounted in the said socket and co-operating with the rib and floor, a remote socket 105 having a wall at an angle, and partial perimetrical vertical shoulders, the ledger plate having a registering configuration mounted in the socket and interlocked therein through the instrumentalities of the angled wall and partial perimetrical shoulders, and an opening in the ledger plate 110 for the reception of a tool to break the interlock. 115

4. As a new article of manufacture, a guard finger for use with a mowing-machine, consisting of guard finger body having a socket with a contoured floor, a fulcrum rib adjacent the entrance on the underside of the top wall thereof, a second socket formed remote therefrom and having a rear wall at an angle, and bounded by partial 120 perimetrical vertical shoulders, an arm extending 125 therebeyond, and a portion having an aperture therein whereby the same may be secured to the mowing-machine. 130
